CLAIM

The ornamental design for a projector lamp as shown and described.

DESCRIPTION

FIG. 1 is a top, front, right side perspective view of a projector lamp, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, bottom, left side perspective side perspective view.

The dashed broken lines in the drawing depict portions of the projector lamp that form no part of the claimed design.
